WELL PERFORATING CONTROL

Warren Gillette Ownby and Kenneth Robison, Houston, Tex., assignors to Camco, Incorporated, Houston, Tex., a corporation of Texas

Filed Sept. 14, 1959, Ser. No. 839,881

5 Claims. (Cl. 166—55.1)

This invention relates to the preparation for operation of fluid producing wells and more particularly to an improved arrangement for directionally perforating from the inside of a tubing string and into a production formation and with direction control for effectively eliminating the likelihood of performing perforating operations in paths to intersect and damage other tubing strings of a multiple completion well.

An object of the invention is to enable two or more production strings to be lowered into final position within a well bore which traverses several production zones and after they have been properly set, cemented and washed, to then perform separate perforating operations from the inside of each tubing string into selected zones respectively for completing the well.

Another object of the invention is to provide for the simplified use of wire line equipment to suspend and lower a perforating gun into proximity to a known depth to be perforated and then to be positioned and oriented through a combined longitudinal and rotational manipulation for controlling the range of a perforating operation within a region away from interference with other tubing strings extended therebelow.

A further object of the invention is to provide a perforating gun having its charges directed for projection within a limited circular segment of its body and a firing system which includes a magneto device whose pole pieces are exposed at the periphery of the body and in fixed relation to the projection direction of the perforating charges and are arranged in coded relation to magnet pole pieces carried within a tubing string region isolated at one side of the tubing string whereby gun travel through the tubing string and alignment of the two sets of coded pole pieces for extending lines of force from the magnet to the magneto device, assures performance of the perforating operation in the desired direction.

Other objects and advantages of the invention should become apparent in the following specification and accompanying drawings wherein FIG. 1 is a vertical section of a portion of a dual completion well illustrating the use of the invention; FIGS. 2A, 2B, 2C and 2D are companion views of the improved perforating device in part side elevation and part longitudinal section and with FIGS. 2C and 2D also showing a fragment of a tubing string nipple in longitudinal section; FIG. 3 is a perspective view partly in section of a portion of a tubing string nipple having a longitudinal row of permanent magnets in a given side region of the circular tubing nipple; FIG. 4 is a diagrammatic vertical sectional view of a well installation involving multiple production tubes with double packers in a cased hole and an alternative arrangement of magnets for controlling the direction of perforation; FIG. 5 is an enlarged view partly in elevation and partly in longitudinal section of a tubing string coupling element on which magnets are located exteriorly thereof; FIG. 6 is a perspective view of a fragment of one of the magnet mounting rings and FIG. 7 is a wiring diagram.

Following the drilling of a well whose bore has penetrated several fluid containing formations as indicated at A, B, C and D in the diagrammatic FIG. 1 illustration, it may be feasible to install separate tubing strings in parallel for completing the well to different formations and also provide for later blocking off a previously com-

2

pleted zone and bringing in another zone through any of the production strings. Accordingly, at least one of the tubing strings should be of a length to traverse all formations and other strings economically can be shorter to reach upper zones, as seen in FIG. 1, and which for convenience shows a pair of tubing strings positioned in an uncased bore wall and set permanently in cement filling the bore hole around the tubes.

To reduce the work and load on installation equipment involved in simultaneously making up two long tubing strings and lowering them as a bundle into a well bore, it is here proposed to make up and lower a single tubing string 1 of a length to pass all of the formations and extend to the deepest thereof. Such string will incorporate in predetermined spaced relation various types of nipples and inserts for co-operation selectively with control accessories of various types. One such insert is a special nipple 2 having a laterally projecting hollow-fitting or offset receiver 3 which carries a dependent tubing section 4 of relatively short length to extend below the receiver 3. A lateral port or side passage 5 in the nipple 2 joins the interiors of the tubing string 1 and the receiver 3 for their selective communication or block-off, depending on flow paths to be established, under control of a suitable tool, as, for example, a hollow flow control device 6 of a wire line retrievable type, removably mounted within the nipple 2 and in sealed relation therewith above and below the passage 5.

Above the communication port 5, the upper open end 30 of the offset receiver 3 has a coupling connection at 7 with the lower end of a second tubing string 8 in alignment with the depending tubing section 4. Additional nipples 2 at other levels in the tubing string 1 and with offset receivers variously circularly spaced, will enable other production strings to be set in the well bore.

As part of the nipple 2, there will be placed in given positions a number of permanent magnets and similar magnet units can be incorporated in other tool receiving nipples in both strings at selected depth locations. The 40 magnet unit 9 in the nipple 2 just above the side opening 5 is shown as having two vertically spaced rows of circularly spaced apart magnets and are for co-operation with a known type of running tool such as that disclosed in patent application S.N. 803,049, filed March 30, 1959, which detachably mounts a control device and is lowered by wire line equipment so that magneto devices embedded in the running tool will be influenced by the magnets upon alignment therewith for releasing and setting within the 45 tubing string any of various types of conventional subsurface well tools such as the flow control device 6 previously described. When a given tubing string has a series of magnet units 9 in spaced apart relation, the vertical spacing of the rows of magnets in each ring usually is different than others so that running tools having pole 50 pieces coded to certain magnet units can be employed for setting tools at selected levels.

The nipple 2 is also shown in FIG. 1 as having immediately below the side passage 5 a pair of magnet units 10, one in each tubing string. In this instance, 55 in addition to vertically spaced apart rows of circularly spaced apart magnets, each unit 10 has at one side thereof a single vertical row of magnets and the several magnet rows are for coded co-operation with field poles associated with magneto devices forming a part of a perforating gun assembly whereby a perforating operation will occur only when the perforating charges are at a given depth and are directed in a predetermined radial direction as will be controlled by alignment of the field poles of the several magneto devices and the pole pieces of the 60 magnets in the several circular and vertical rows, as will later be referred to in greater detail. For permitting selective perforation at any of several productive forma-

tions traversed by a well bore, several magnet units 10 differing from one another as to spaced locations of the rows of magnets will be incorporated in a tubing string at given depths related respectively to the formations.

After the multiple tubing string assemblies have been lowered to the desired positions in the well bore, they can be cemented in place by known procedures by which a cement slurry is directed, for example, through the tubing string 1, into the open hole so as to fill the bore hole surrounding both tubing strings and provide a solid plug 12. The bottom of the extension tubing 4 may be closed by a suitable plug against entry of cement slurry and after the cement has set a perforating gun will be lowered through the string 1 for forming the flow openings 11 into the lowermost formation A. Such perforating gun can be hung in spaced relation corresponding to the known distance between the formation A and the magnet assembly 10 next thereabove and from a wire line running tool having magneto devices to be influenced as hereinafter described by the magnet assembly 10 within the tubing string 1. Perforations into an upper formation B are also performed by a wire line suspended device and controlled directionally so as to pierce and complete flow passages into the formation on radial lines angularly spaced away from intersecting relation with the downwardly projected tubing 1. Well working devices can then be used for producing both zones and for performing various workover operations. Reworking can include closing off previously completed zones and new perforating jobs at other zones at which gun controlling sets of magnets in tubing nipples were provided.

In FIG. 2C there is indicated the detail of a magnet assembly 10. A tubing string nipple portion 13 is shown with an internal counterbore or pocket which receives in succession a magnetic spacer tube 14, a nonmagnetic ring 15, a magnetic spacer ring 16, a nonmagnetic ring 17 and a series of magnetic spacer rings 18. Examples of magnetic materials include iron and soft steel and of nonmagnetic materials include copper, aluminum and resin plastics. The longitudinal lengths of the several rings 15-18 can be of predetermined dimensions and the rings can also be interchangeably related so that the upper nonmagnetic ring 17 can be variously spaced axially in equal steps from the lower nonmagnetic ring 15. Adjustment in such spaced relation will enable a selective coding of the parts to similarly equally spaced elements of control parts which are to respond to the magnetic fields of permanent magnets 19 and 20 fixedly inserted in the nonmagnetic rings 17 and 15 and comprised of short plugs or discs that extend radially through the respective carrier rings and are circularly spaced apart in annular rows. The inner and outer faces of the magnets 19 and 20 are of opposite polarity and in each instance the lines of force between opposite pole faces extend through the nonmagnetic carrier ring and protrude inwardly of the innermost pole and into the hollow tubing string space.

Isolated to one side of the tube 14 and fitted within a longitudinally elongated opening, there is a nonmagnetic strip 21 having projected therethrough a number of permanent magnets 22 vertically spaced apart in a single longitudinal row and the lines of force between the inner and outer end faces of these magnets will loop into the interior space of the tubing string and pass through the nonmagnetic carrier strip 21. When the fields of all three groups of magnets 19, 20 and 22 are simultaneously extended to influence magneto devices, there can be signaled the performance of work such as the well wall perforating operation. Each such magneto device can control the closing of switch contacts serially connected in an electric control circuit for supplying current in a firing circuit to fire the explosive charges of a perforating gun. The gun with a set of magnetic devices attached thereto, consists of a wire line tool to be passed through

the tubing string and fired upon simultaneous closing of the serially connected switch contacts.

The three switches indicated at 23, 24 and 25 each constitutes the magneto device referred to and operates under the di'Arsonval principle. Each has a current receiving coil pivoted to respond to a magnetic field across field pole pieces on opposite sides of the coil for closing a pair of contacts. Such pole pieces for the switch 25 are indicated at 26 and 27 and are for lateral alignment with any of the series of plugs 28 arranged in proper vertically spaced relation in the wall 29 of the body of a wire line running tool assembly. This upper switch assembly can be variously adjusted longitudinally of the body for alignment of its field poles 26 and 27 with any selected pair of plugs 28 for selectively modifying the spaced code relation between the two switches 25 and 24. The pole pieces of the lower switch 24 are fixedly mounted in alignment with magnetic plugs 30 carried by the wall 29. Such fixed mounting results from lateral seating shoulders suitably formed on the switch 24 and the wall 29, together with the use of locating spacer sleeves 29a lining the interior of the body wall 29 above and below the switch unit 23, as seen in FIG. 2C.

In the arrangement shown, the spacing of the several pole pieces for the two switches 25 and 24 is in coded relation to magnets 19 and 20 whereby both switches would be closed. However, the lower switch 23 is not closed since the ends of its pole pieces, comprising two circularly spaced rows of vertical plugs 31, are circularly displaced from radial alignment with the effective fields of the single vertical row of magnets 22. In other words, a rotational adjustment of the running tool from the relative position illustrated in FIG. 2C, effected by rotational manipulation of its suspension wire line will be needed to bring the field pieces 31 into field relation or radial alignment with the magnets 22 for influencing the magneto switch 23 and completing a control circuit through all switches concurrently to actuate a suitable relay and close a firing circuit for the perforating gun.

The perforating gun 32 of a generally conventional type, as seen in FIG. 2D, has one or more vertical rows of radially directed perforating charges or shot 33 in a predetermined circular region and its upper end is illustrated as being fixedly secured to the lower end of the running tool body 29 and to constitute a solid unit therewith. Its explosive charges are connected to be fired by current supplied through a conduit 34 in a relay circuit controlled by the series connected switches 23, 24 and 25 which need to be closed concurrently to complete the circuit containing the relay. Because of the nonrotatable and spacer mounting connection between the perforating gun 32 and the running tool body 29, there will be a fixed angular and longitudinal relation between the locations of the perforating shots 33 and the pole pieces 31 and direction of force projection through the tubing is positively controlled by the location of the set of magnets 22 oriented at one side of the tubing.

For coding to any desired one of a series of tubing insert members or nipples having differently spaced magnets and by changing the vertical spaced relation between the switch units 24 and 25, the upper unit 25 is fastened to the lower end of a vertically shiftable post 35 which extends upwardly in the tool body 29 and, as seen in FIG. 2B, has a key 36 projecting outwardly therefrom through an elongated slot 37 in the body 29. On its outer face, the key 36 carries helical thread formations fitted to internal screw threads on a rotary sleeve 38 carried in a reduced diameter portion or annular notch in the exterior wall of the body 29 and normally protectively enclosed within an axially shiftable outside sleeve 39. Near its upper end, the outer sleeve 39 is internally threaded to engage co-operating threads at 40 on the body wall 29. To effect a desired setting before a tool is run into a well, torque is applied manually to the sleeve 39 for rotating the same and unthreading it from the

screw threads 40 to thereby separate and allow the sleeve 39 to slide down and expose the manually rotatable sleeve 33. Rotation of the sleeve 33 by reason of its threaded engagement with the key 36 is converted into longitudinal movement of the switch adjusting post 35 for a selective position setting of the switch unit 25 in code relation to the switch unit 24. After such setting, the sleeve 39 is raised and recoupled on the threads 40 in protective overlying relation to the rotatably adjustable sleeve nut 38.

In the upper hollow part of the body 29, there will be located the electrical components, including such items as the batteries B1 and B2, the relay R and a master switch 41 whose circuitry is diagramed in FIG. 7. These electric batteries are sources for supplying current to the coils of the magneto devices 23, 24 and 25, to a relay actuating circuit controlled by the magneto switches and to the relay controlled detonating circuit. A manually controlled master safety switch is located within the top of the tool body and includes a two position microswitch 41 which can be shifted between its positions upon relative movement of its upwardly extending post 42. In one position the gun detonators are grounded and all battery circuits are opened and the other position, established when the tool is about to be lowered, closes the battery circuits. Post movement in an upward direction is under influence of a coil spring 43 when a lateral screw stud 44 is backed out of engagement with a conical head end on the post 42. By reason of the co-operating tapered ends of the stud 44 and post 42, an inward threading of the post 44 will depress the post 42 against the resistance of the spring 43.

As previously indicated, when all three of the magneto devices or magnetically set switches 23, 24 and 25 are simultaneously influenced by magnetic fields, then electric current is transmitted to the perforating device, as will readily be apparent from the circuit diagram of FIG. 7. Here the manual switch 41 is represented as a grounded blade movable between two contacts, one of which is normally closed and grounds both sides of the squib or detonator 33' for safety purposes. This grounded switch blade also has connection through each coil of the magnetically set switches 23, 24 and 25 with a positive tap on the battery B1 and connection by way of serially joined switch contacts of the switch units 23, 24 and 25 and through the coil of the relay R1 with the positive terminal of the battery B2. Both batteries have their negative terminals joined to the other or normally open contact of the manual switch 41. To condition the control system for operation, the switch 41 is shifted to open its normally closed contact and to close its normally open contact. Thereupon, current from the battery B1 flows through the parallel coils of the magnetically set switches 23, 24 and 25 and biases the pivotally mounted coils against swinging movement from positions holding open their respective contacts. The tool unit suspended by a wire line can now be lowered into a well tubing string incorporating sets of differently spaced apart magnets. As these magnets are traversed during tool descent, their fields individually will be impressed on each movable switch coil and the coil under influence of the field will swing to close its contacts. Closure of any one of three series connected switches while any other of the two switches is open is ineffective for current flow in the circuit containing the coil of the relay R1. By reason of selective position adjustment of the switch 25 through its shiftable post 35 and the rotary sleeve nut 38, the spaced apart relation of the pole pieces of the switches 23, 24 and 25 will have been preset to match the space apart fields provided by a particular set of the several sets of magnets 22, 20 and 19 in the tubing string, whereby all three of the series connected coils of switches 23, 24 and 25 will be simultaneously influenced by magnetic fields only when the tool descends to the pre-selected set of magnets. Concurrent closing of the series connected switches enables battery B2 to energize the

relay R1 for directing current from the battery B1 to the detonator 33' for firing the same.

To summarize the performance of a perforating operation and considering zone B of FIG. 1 is to be opened for production through the tubing string 8, the selector sleeve 38 on the running tool will be adjusted as required to preset the position of the relatively adjustable switch unit 25 in order to present its pole pieces in given axially spaced apart relation to the pole pieces of the fixedly positioned switch unit 24 and which given spaced relation matches the known axial spacing between the fields of the pair of circularly arrayed magnets 19 and 20 in the nipple 10 next adjacent and above zone B. The gun perforator 32 will be fixedly attached to hang on the tool body so as to place the perforating charges 33 below the switch unit pole piece plugs 31, 30 and 28 a distance corresponding with the known vertical spacing between zone B and the fields of the magnets 22, 20 and 19 and also to fix the laterally directed perforating charges 33 in predetermined angular relation with the switch pole pieces 31 which, as previously indicated, are purposely oriented at one side of the tool wall. As was heretofore pointed out, such angular relationship insures aiming of the perforating charges at the time of subsequent firing in the desired direction out of intersecting relation with the tubing string 1. Finally, the safety switch 41 is shifted from its grounding position illustrated in FIG. 7 to its other position in which the circuits are conditioned for closing the firing circuit and the tool and gun assembly is lowered within the tubing string 8. When suspension line pay-out and tool descent brings the gun perforator within zone B, as seen in FIG. 1, the pole pieces 28, 30 and 31 will be disposed for co-operation with the fields of magnets 19, 20 and 22. If these pole pieces come within the fields in concert, the responsive actions of the field coils for the series connected switches 23, 24 and 25 effect switch actuation to energize the relay R1 for closing the gun firing circuit. Firing will not occur should the pole pieces 31 be angularly displaced from and outside the fields of magnets 22. Control of the direction of firing is by relative disposition of the oriented magnets and pole pieces and since the tool is suspended by wire line, it is not stabilized against turning about its longitudinal axis and it is free to swing and present its pole pieces 31 within the fields of the fixedly mounted magnets 22 to effect the firing when the charges are aimed away from the tubing string 1. Swing can be imparted to the tool through the wire line by its manipulation at the wellhead and rotation of the line can be accompanied by some reciprocation for placing all the pole pieces within magnetic fields in unison.

Preferably, the relatively delicate control switches and other electrical components contained within the running tool are protected from mechanical shock by filling the housing with a suitable liquid and by balancing internal and external pressures in the manner illustrated in FIG. 2B, where the annular space between the post 35 and the housing 29 forms a part of the liquid enclosing chamber and which is closed by a piston or slide ring 45 operating within this annular space and exposed on one side to the filling liquid and on the other side to outside pressure at the wall opening 46.

An arrangement especially adapted for directionally perforating a formation from within a cased hole and between packers in a multiple completion installation is illustrated in FIG. 4. The well hole 50, to be considered as lined by a casing 51, traverses several potential producing horizons, such as shown at X, Y and Z. A bottom packer 52 is illustrated as being set between the formations Y and Z and around a relatively long production tubing string 53, the side wall of the hole having been perforated at 53' into the producing formation Z served by the string 53. A second tubing string 54 extends through the well hole in side by side parallelism with the production string 53 and terminates at its lower end at some predetermined distance above the bottom packer 52.

An upper packer 55 surrounds both strings 53 and 54 to seal off the well hole at a distance above at least one of the upper fluid containing formations X and Y. The drawing illustrates formations X and Y in the space between the packers and perforations can be performed into either of these horizons for producing the well through the tubing string 54.

One, but preferably both, of the tubing strings will be made up with nipples containing magnets for selective actuation of tool setting equipment having magneto devices as previously described, the magnets and setting tools being properly coded one to another. A pair of such magnet carrying nipples are diagrammatically shown at 56 in both tubing strings.

More particularly, the longer tubing string 53 in its downwardly projected portion between the packers 52 and 55 and in predetermined relation with each fluid containing formation, such as X and Y, is provided on the exterior thereof with groups of magnets arranged in coded sets for controlling actuation of a perforating tool diagrammatically indicated at 57 and constructed essentially as heretofore described and shown in FIGS. 2A-2D. In other words, the tool will include a perforating gun having one or more ignitable charges directed to project outwardly on radial paths and also having a detonation circuit under control of magneto switch means with outwardly facing pole pieces at least certain of which are segregated and isolated at one side of the tool in angularly spaced relation with the radial paths of projection of the perforating charges. In this instance, the tool 57 is to be suspended on the lower end of a wire line 58 for lowering and turning manipulation through the tube 54 to below the lower end thereof and into lateral alignment with the formation selected for perforating.

Because of the relative angular relationship of the charge and the pole pieces in the tool 57, the gun, after having been lowered to a point adjacent the selected formation, will need to be manipulated through the suspension wire line 58 so as to effectively line up, both vertically and laterally, the coded pole piece terminals of the tool with the field of actuating magnets and when this is done, the charge will be fired and its path of projection controlled so as not to intersect any part of the tubing string 53.

For mounting the actuating or control magnets on the exterior of the tubing string 53, a special connector nipple or tubular coupling 59, as seen in FIG. 5, may be employed. Its opposite ends are threaded for insertion within the tubing string and it has near one end an exterior locating shoulder 60 for a set of rings, sleeved one after the other on the outside of the body of the coupler 59. Such rings, as shown, include a pair of nonmagnetic collars 61-61, each having a series of disc or plug magnets 62 arranged in a circular row. Co-operating with the rings are a number of magnetic spacer collars 63 which can be variously sequentially positioned for changing the spaced relation selectively between the upper and lower nonmagnetic collars 61 for coding purposes. In addition, there is a longitudinally extended collar 64 of magnetic material which has circularly spaced elongated slots angularly spaced apart at about a forty-five degree angle. Within each vertical slot is located a nonmagnetic insert strip 65 for carrying a vertical row of spaced apart magnets 66. In this instance the magnetic lines of force between the opposite polarity end faces of the magnets pass through the nonmagnetic strip 65 and protrude into the space surrounding the tubing string 53. As seen in FIG. 6, the magnets are of frusto-conical rod shape and fit within outwardly tapered openings in the nonmagnetic strips 65 to insure retention. An end collar or ring 67 may carry a suitable set screw for fastening it securely to the coupler 59 and for maintaining the several rings in tight stacked relation one with another and with the uppermost ring against the stop shoulder 60.

When three magnetic switches in series connection, as

shown in FIG. 2C, are employed with the perforating gun, the magnets in the two rings 61-61 will supply fields to two of the switches and one row of magnets 66 will supply the field for the third magneto switch and whose field poles, as previously described, are isolated in one side of the tool. Because of the impracticability of being able to set a long tubing string so that a given circular region thereof at a low point is certain to be at a given radial position, it is here proposed to provide the collar 64 with several vertical rows of magnets circularly spaced apart with a small enough intervening angle that one of the rows will present itself on the side of the tubing string 54 for co-operative relation with the isolated magnet poles of a gun brought into the firing region. This insures action of the perforator in a direction other than one which would pierce the tubing string 53.

What is claimed is:

1. Equipment for controlling directional well perforating operations, including a well tubing string member, a permanent magnet carried by said member at a selected side thereof with a pole thereof terminating at the member interior surface and establishing a magnetic field across a limited transverse zone of said interior surface and transversely of the longitudinal direction of the member, a wire line suspended device for travel passage within the tubing string member, magneto means in said device, pole pieces therefor having terminal faces spaced apart transversely to its direction of travel passage and confined to a selected side zone in the peripheral face of the device for the extension of said magnetic field to the magneto means upon lateral alignment of said terminal faces with the magnetic field, a wire line suspending said device for travel and constituting a control through which said lateral alignment may be established, a perforating tool secured to said wire line suspended device, perforating means positioned on said tool for action in a restricted given lateral direction in fixed relation to the selected side zone location of said terminal faces and operating means for said perforating means connected with and influenced by said magneto means to actuate said perforating means upon response of the magneto means to said magnetic field.

2. Equipment for controlling directional well perforating operations including a plurality of well tubing strings in side by side relation in the same well bore, a magnet carrying nipple located at a predetermined depth in one of the tubing strings, a magnet in said nipple having pole pieces isolated within a given sector of the nipple, a perforating tool adapted to be lowered through said one of the tubing strings, perforating means carried by the tool and directed for performing a perforating operation laterally thereof within a given circular segment of the tool, a magneto control operative to effect the action of said perforating means and mounted as a self-contained part of said tool, field poles for said magneto control terminated at the periphery of the tool and fixed in circular relationship to said given circular segment to compel relative tool adjustment into position in which the direction of perforating operation of said perforating means is away from intersecting relation with other tubing strings upon alignment of said field poles with the isolated pole pieces of said magnet and tool positioning means through which said tool adjustment is effected.

3. For the performance of directional well perforating operations, a well tubing string, a series of magnet carrying nipples at spaced apart depth intervals in the tubing string, spaced apart pole pieces in each nipple in differently spaced apart relation in the several nipples for coded actuating relation with different well tools selectively, one of such tools being a perforating gun having an electrically actuated perforating charge mounted for projection in a predetermined direction, magneto devices controlling charge actuating current flow to said charge and being carried by said gun, said magneto devices having pole pieces spaced apart in coded correspondence with the

spaced apart relation of the magnet pole pieces of a selected one of said nipples, the pole pieces of one of said magneto devices being in fixed angular relation to said predetermined direction of charge projection and a number of the last mentioned magnet pole pieces to which the pole pieces of said magneto device are coded being positioned by said selected one nipple for orienting the gun to a given charge projection direction relative to the said selected one nipple and gun positioning means operable to establish gun position for charge projection in said given direction.

4. In combination, a well tubing string having a number of magnet carrying nipples at spaced apart depth intervals and with pole pieces spaced apart in coded relation to different well tools to be actuated in response to receipt thereby of magnetic lines of force, one of said nipples having its magnet pole pieces located for the presentation of lines of force only in an isolated side region of the nipple, a perforating gun for co-operation with the last mentioned nipple, a magneto device contained in the gun and provided with pole pieces isolated within one side of the gun to compel a given rotational position of the gun for influencing said device by the magnetic lines of force through alignment of the pole pieces of the gun and the nipple, means operable on the gun and controlling said given rotational position and perforating means responsive to said magneto device and mounted by the gun to perform a perforating operation within a zone fixed in relation to the isolated side location of the pole pieces of such magneto device.

5. For the actuation at selected levels of well tools having magneto devices and pole pieces therefor variously spaced apart, a pair of tubing strings extending through a well hole, sets of magnets positioned in the tubing strings at predetermined depths and spaced apart in coded rela-

5

10

tion with pole pieces of certain well tools, one tubing string extending to a depth to produce from an upper formation and the other tubing string extending to a depth to produce from a lower formation, said other tubing string having sets of magnets exteriorly thereof and in a region in given relation to the upper formation, one of said sets of magnets comprising a number of vertical rows of vertically spaced apart magnets whose spaced apart relation is alike in all rows and which rows are angularly spaced apart so that regardless of rotational positions of said tubing string, there will be one of the several vertical rows of magnets adjacent a region longitudinally aligned with said one tubing string, a perforating gun to be lowered through said one tubing string to the level of the upper formation and having a laterally projectable charge and magneto means controlling the firing of said charge and having pole pieces arranged in sets which are spaced apart in coded correspondence to the sets of magnets which are exteriorly of said other tubing string, one of said sets of pole pieces being isolated in a side of the gun angularly spaced from the projection path of said charge and gun suspension means operable to control gun position for presentation of the side isolated pole pieces within the field of said one row of magnets.

25

30

35

tion with pole pieces of certain well tools, one tubing string extending to a depth to produce from an upper formation and the other tubing string extending to a depth to produce from a lower formation, said other tubing string having sets of magnets exteriorly thereof and in a region in given relation to the upper formation, one of said sets of magnets comprising a number of vertical rows of vertically spaced apart magnets whose spaced apart relation is alike in all rows and which rows are angularly spaced apart so that regardless of rotational positions of said tubing string, there will be one of the several vertical rows of magnets adjacent a region longitudinally aligned with said one tubing string, a perforating gun to be lowered through said one tubing string to the level of the upper formation and having a laterally projectable charge and magneto means controlling the firing of said charge and having pole pieces arranged in sets which are spaced apart in coded correspondence to the sets of magnets which are exteriorly of said other tubing string, one of said sets of pole pieces being isolated in a side of the gun angularly spaced from the projection path of said charge and gun suspension means operable to control gun position for presentation of the side isolated pole pieces within the field of said one row of magnets.
